UNITED STATES PATENT OFFICE.

LAWRENCE LANGNER, OF NEW YORK, N. Y.

LIGHTING APPLIANCE.

1,224,386.

Specification of Letters Patent.

Patented May 1, 1917.

Application filed February 3, 1915. Serial No. 5,910.

To all whom it may concern:

Be it known that I, LAWRENCE LANGNER, citizen of the United States, and resident of New York city, in the county of New York 5 and State of New York, have invented certain new and useful Improvements in Lighting Appliances, of which the following is a specification.

This invention relates to improvements in 10 lighting appliances of the well-known "semi-indirect" type, that is appliances in which the lighting of a room is obtained partly by transmitted light, and partly by reflection from a ceiling or like reflecting surface. 15 As a general rule, this reflection is obtained from an ordinary ceiling by hanging the globe or dome in relatively close proximity to the ceiling. The globes or domes used in lighting systems of this character are generally made of translucent glass having good 20 light-transmitting qualities, such as the well-known Alba glass, and the total illuminating effect produced by the lighting appliance is dependent in most cases upon the 25 light-transmitting quality of the glass employed, this transmitted light predominating over the reflected light in producing the desired illumination.

Domes or globes of the character employed for "semi-indirect" lighting suffer 30 from the disadvantage that dust tends to collect in the interior of the dome, thereby preventing the transmission of light through the dome, so that the quality of the illumination 35 produced by direct light transmission is materially impaired. This results in a general loss of illumination, notwithstanding the fact that no obstacle is presented by the dust to the reflection of light, because as 40 stated above, the value of the illumination is for the most part dependent upon the amount of light transmitted rather than upon the amount of light reflected. It is a matter of extreme difficulty to clean such 45 domes or globes, owing to the fact that they must be mounted relatively close to a ceiling or the like, in order that the light may be reflected from the ceiling into the room with the desired amount of diffusion. Apart 50 from the inaccessibility of the dome, it is also an extremely difficult matter to clean the dome when hanging in its normal position, owing to its shape, which is generally like that of a bowl, making it almost impossible 55 to clean the dome with a duster, as the dust tends to cling to the bottom and

side-walls of the dome. The best way to clean such a bowl is to take it down from the ceiling, invert it, empty out the dust and then wash it.

Now the object of the present invention is to so improve upon "semi-indirect" lighting appliances as to prevent losses in transmitted light and to render the cleaning of the appliance a relatively simple matter, which 60 can be performed without difficulty, notwithstanding the inaccessible location of the dome or globe. A preferred embodiment of the invention will now be illustrated with reference to the accompanying drawing, 65 which shows a dome for "semi-indirect" lighting, provided with a single electric lamp, the dome being partly broken away and certain of the parts including the lamp-holder being shown in section.

Referring to the drawing, 1 represents the ceiling, to which is attached in well-known manner the mounting 2, from which hang chains 3, engaging with a metal ring 4, supporting the annular bowl-shaped glass dome 5, made of Alba glass or any other suitable translucent light-diffusing and transmitting glass. Over the top of this dome and forming a closure thereto, I place a circular plate 9, made of clear transparent glass, mica or the like, and preferably though not necessarily, curved as shown. This glass plate is formed with an opening in the center thereof, the bore of which is sufficiently wide to permit of the insertion of the well-known 90 electric incandescent lamp 10, screwed into the usual socket 11 and connected by the conductor 15 with the source of current-supply in well-known manner. Beneath the socket 11, I arrange a plate 12, which is preferably, 95 though not necessarily, made of light-transmitting material, such as clear transparent glass, and this plate 12 is formed with a bore 13, adapted to take under the socket 11 of the electric lamp fixture. In assembling 100 the above lighting appliance, the dome with the plate 9 in position is secured to the ceiling in well-known manner. The threaded portion 14 of the electric lamp is inserted through the bore 13 of the plate 12, after 105 which the lamp is inserted in the opening in the large plate 9 and screwed into the socket 11. The plate 12 therefore serves as a simple means of mounting the electric lamp in the dome. It will be apparent that two or 110 three openings may be provided in the plate 9, when it is desired to employ a number of

incandescent lamps, thus doing away with the necessity of providing metallic fixtures for holding the lamps in the dome.

In the use of the above described lamp fixture, the dust which would ordinarily tend to gather in the bowl-shaped portion of the lamp, thereby interfering with the important light-transmitting qualities of the illumination is prevented from so doing by the glass plate 9, and the dust will tend to settle upon this glass plate, where, of course, it will tend to interfere with the relatively unimportant light-reflecting quality of the illumination. Owing to the smooth surface of the clear transparent glass and also to its curved shape, the dust will tend to fall off this surface, especially by reason of the circulation of air in the room in which the fixture hangs. Such dust as may remain on this glass plate will not seriously affect the total illuminating qualities of the appliance, inasmuch as the transmitted portion of the light which is relied upon to give the greatest illuminating effect is protected from the dust. A further advantage of the improved fixture resides in the fact that the glass plate 9 in addition to supporting the lamps may also serve to support the electric conductors, so that such conductors will not fall into the dome-portion where they would show through as black shadows on the dome. Moreover, none of the electric lamp supporting fixtures will throw shadows on the dome.

The lighting appliance in accordance with my invention, when it does require cleaning, which may occasionally be the case, can be readily cleaned without removing it, as all that is necessary to do is to take a duster and wipe the plate 9, which can be done without difficulty, notwithstanding the inaccessible position of the dome near the ceiling. The replacement of an electric lamp can also be effected without removing the plate 9.

While I have described the plate 9 as being made of clear transparent glass, it is apparent that it might equally be made of Alba glass or similar glass, though it is preferable to use a clear transparent glass. However, in certain cases it may be desired to have the color of the reflected light different from that of the transmitted light, in which case the plate 9 might be made of suitable colored glass, for instance, amber glass, as a result of which special and pleasing light effects can be obtained. The invention is also applicable for use in gas-lighting appliances. While I have shown the plate 11 supporting the electric lamp, it is apparent that other means might be employed for that purpose. It will also be obvious that the plate 9 need not be made in one part, as shown herein.

I wish it to be understood that my invention is capable of numerous modifications, as 65 will be apparent to those skilled in the art,

and I do not intend by the claims which follow to limit myself to the specific form of the invention herein described and illustrated.

What I claim is:—

1. In a lighting appliance, a bowl of translucent glass, means for suspending said bowl, a detachable glass plate formed with an opening therein supported by the upper part of said bowl, a lamp extending through said opening, a socket for said lamp, and a member interposed between said lamp and socket bearing on said glass plate and closing the opening therein. 70

2. In a lighting appliance, a bowl of translucent glass, means for suspending said bowl, a glass plate formed with an opening therein supported by the upper part of said bowl and a lamp extending through said opening and supported by said plate. 80

3. In a semi-indirect lighting appliance, an open bowl of translucent glass, a plurality of flexible means connected with the periphery of said bowl to suspend said bowl, a detachable light-transmitting means overlying said bowl, supported at the periphery of said bowl, and adapted to be removed from said bowl by passing it between said flexible means, a lamp within said bowl and beneath said light transmitting means, and a flexible 95 conductor connected to said lamp. 90

4. In a lighting appliance, a bowl of translucent glass, means engaging with the periphery thereof for suspending said bowl, and a readily detachable glass plate having a relatively large opening therein resting on and supported by the upper part of said bowl, said bowl and plate inclosing a space, and a lamp in said space supported from said plate. 100

5. In a semi-indirect lighting appliance, an open bowl of translucent glass, means for suspending said bowl from the periphery thereof, transparent light transmitting and dust excluding means located at the upper portion of said bowl supported in position entirely at the periphery of said bowl, and having an opening therein, said bowl and last mentioned means together inclosing a space, a lamp in said space and means between the lamp and light transmitting means covering the opening in the latter. 110

6. In a lighting appliance, a bowl of translucent glass having an open upper portion, means for supporting said bowl, lamp supporting means comprising a transparent surface arranged over said open portion, and a lamp supported by said supporting means and inclosed between said supporting means and said bowl. 120

7. In a lighting appliance, in combination a bowl of translucent glass having an open upper portion, and lamp supporting means comprising a transparent surface arranged over said open portion. 130

8. In a semi-indirect lighting appliance, a bowl of translucent glass, a glass plate formed with an opening therein and located over the upper part of said bowl, a lamp extending into said opening, and means supported by said plate for supporting said lamp.
9. In a lighting appliance, a bowl of translucent glass, means for suspending said bowl from the periphery thereof, a detachable light transmitting and dust excluding means formed with an opening therein and covering the top of said bowl, a lamp extending through said second mentioned means and flexible supporting means for said lamp whereby said lamp may be removed through said opening.
10. In a lighting appliance, a bowl, a light transmitting means forming a closure for the upper open portion of said bowl, and a lamp within the space inclosed between said bowl and light transmitting means, said

- lamp supported by said light transmitting means.
11. In a lighting appliance, a bowl of translucent glass, means for suspending said bowl from the periphery thereof, and light transmitting means overlying said bowl and adapted to serve as a support for a lamp inclosed between said bowl and said light transmitting means.
12. In a lighting appliance, a bowl of translucent glass, means for suspending said bowl, a light transmitting means arranged to overlie the opening of said bowl, and a fixture on said light transmitting means adapted to receive and support a lamp.

Signed at New York city in the county of New York and State of New York this 28th day of January A. D. 1915.
